UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE.

1,285,653.

Specification of Letters Patent. Patented Nov. 26, 1918.

Application filed January 2, 1918. Serial No. 210,004.

To all whom it may concern:

Be it known that I, ALBERT ERICKSON, a citizen of the United States, residing at Chicago, in the county of Cook and State of Illinois, have invented certain new and useful Improvements in Ignition Devices, of which the following is a specification, reference being had to the accompanying drawing.

10 The invention relates to new and useful improvements in ignition systems and more particularly to an ignition system having an ignition generator wherein the rotor or armature shaft is oscillated for furnishing 15 current to produce the sparks for ignition.

An object of the invention is to provide an ignition system of the above character wherein the rotor shaft and the trip lever for actuating the same are both moved by 20 a torsional spring which is preferably arranged coaxial with the trip lever and shaft.

A further object of the invention is to provide mechanism of the above character wherein the movable electrode of the ignition 25 device is actuated by a member disposed between the trip lever and the movable electrode, which member is normally out of contact with the arm on the movable electrode so as to permit the ignition points 30 to remain in contact as they wear.

A further object of the invention is to provide a device of the above character wherein the member disposed between the trip lever and the movable electrode is 35 forced toward the trip lever by a spring which is of slightly greater tension than the torsional spring when in its released position so that said member may be moved away from the movable electrode.

40 A still further object of the invention is to provide a device of the above character wherein the torsional spring is supported by a part moving with the trip lever and wherein the torsional spring is also provided 45 with a roller which bears against the trip lever.

A still further object of the invention is to provide an ignition system of the above character wherein the ignition electrodes are 50 mounted in a bracket adapted to be attached to the engine cylinder and wherein the generator is supported on a projecting rod carried by the bracket which rod engages a perforated lug formed integral with the 55 housing for the rotor.

These and other objects will in part be

obvious and will in part be hereinafter more fully disclosed.

In the drawings:

Figure 1 is a view partly in front elevation and partly in vertical section showing a device embodying my invention;

Fig. 2 is a sectional view on the line 2—2 of Fig. 1;

Fig. 3 is a view showing in perspective certain of the parts, said parts being detached and separated from each other;

Fig. 4 is a vertical sectional view through a portion of the trip lever the adjacent part of the bracket supporting the same and the end of the rotor shaft;

Fig. 5 is a view similar to Fig. 4, but showing a slightly modified form of the invention.

In carrying out the invention I have provided a supporting bracket which is adapted to be attached to the outer wall of the cylinder of the engine. Mounted within this bracket are ignition electrodes carrying ignition points and one of the electrodes is movable. Extending outwardly from the bracket is a rod which supports the generator preferably by means of a perforated lug formed integral with the housing of the rotor which lug is keyed to the rod and held thereon by a clamping nut. Also projecting outwardly from the bracket and in alignment with the axis of the rotor shaft is a second rod on which the trip lever is mounted to turn freely. The trip lever is connected to the rotor so that the two move as one. Said trip lever has a projecting sleeve around which is located a torsional spring which is co-axial with the trip lever and rotor shaft. One end of this spring is connected to the bracket while the other end carries a roller bearing on the trip lever. The trip lever operates directly upon a sliding rod which is adapted to be struck a blow by the trip lever and the endwise movement of the rod through the action of said trip lever moves the electrode to separate the ignition points. This sliding rod is

spring pressed toward the trip lever and a stop collar limits its movement. The tension of the spring may also be varied so that said spring in tension is slightly greater than the tension of the torsional spring when the trip lever is in idle or released position. This enables the sliding rod to move to its limit toward the trip lever and thus carry the end thereof out of engage-

ment with the movable electrode so as to permit the ignition points as they wear to always be in contact.

Referring more in detail to the drawings, my improved ignition system includes a supporting bracket 1 which is bolted to the outer wall of the cylinder of the engine in the usual way. Projecting inwardly from the bracket is a member 2 which extends through a suitable opening in the cylinder wall and located in this member 2 are ignition electrodes which are indicated at 3 and 4 in Fig. 2 of the drawing. At the inner end of electrode 4 is provided an arm 5 carrying an ignition point 6 which is adapted to contact with an ignition point 7 on the electrode 3. The electrode 4 is movable so as to separate the ignition points 6 and 7 and again bring the same into contact. On the outer end of the electrode 4 there is an arm 8. A spring 9 encircling the electrode 4 is connected to the bracket at one end and at the other end to the electrode. This spring operates to normally hold the ignition points in contact. The movable electrode is held seated in the usual manner.

Projecting outwardly from the bracket 1 is a rod 10. This rod 10 is rigidly secured to the bracket in any suitable way. Mounted on the outer end of the rod 10 is a magneto generator indicated at G in the drawings. Said generator includes magnets M and a rotor, the rotor shaft supporting the rotor being indicated at 11. Extending about the rotor is a rotor housing 12 which is of the usual construction. Formed integral with the rotor housing is a perforated lug 13 through which the rod 10 extends. This lug, as clearly indicated in the drawings, is located within the U-shaped magnets M. The rod 10 is formed with a reduced section 14 which provides a shoulder 15. The lug seats against the shoulder 15 and is held thereagainst by a nut 16 which is threaded onto the outer end of the reduced section 14 of the rod. The rod is preferably formed with a key-way which is adapted to register with the key-way in the lug and a locking key 17 extended into said key-ways prevents the magneto generator from movement axially about the rod 10.

Also projecting from the bracket 1 is a second rod 18 which may be secured to the bracket in any suitable way so as to be rigidly held thereby. This rod 18 is in co-axial alignment with the axis of the rotor shaft 11. Mounted to turn freely on the rod 18 is a trip lever 19. The trip lever 19 has an inner recess 20 which fits onto the rod 18. The trip lever 19 has a coupling member 21 which is connected to the coupling member 22 on the rotor shaft 11. The rotor shaft coupling 22 is formed with oppositely disposed recesses 23-23. The coupling member 21 is formed with projecting lugs

24-24 which are adapted to extend into and fit the recesses 23 and in this way the trip lever is locked or engaged with the rotor shaft so that the two turn as one. At the same time the rotor shaft may be readily disconnected from the trip lever. Extending from the other side of the trip lever is a sleeve 25 which is preferably formed integral with the trip lever. This sleeve surrounds the rod 18 and preferably extends from the trip lever to the bracket 1 so that the trip lever is offset from the bracket. Extending about the sleeve 25 is a torsional spring 26 which is co-axially arranged with the trip lever and the rotor shaft. The inner end 27 of the torsional spring is connected to the bracket. The outer end 28 of the torsional spring carries a roller 29 which bears against the outer face 30 of the trip lever 19. This roller 29 has a projecting flange 31 which extends along the side edge of the trip lever and the flange serves to retain the roller on the face of the trip lever.

Disposed between the arm 8 of the movable electrode 4 and the upper end of the trip lever 19 is a sliding rod 32. Said rod slides in the bearing lug 33 formed on the bracket and also in the sleeve 34 which is threaded into a bearing lug 35 formed on the bracket. The outer end 36 of the rod is adapted to bear against the trip lever when said trip lever is in idle or released position as shown in Fig. 2. Secured to the sliding rod 32 is a collar 37. This collar is adapted to engage the bearing lug 33 and serves as a stop to limit the movement of the rod toward the trip lever. A coiled spring 38 extending about the sliding rod 33 bears against said collar 37 and at its other end against the sleeve 34. This spring normally forces the rod to the right, as viewed in Fig. 2, holding the collar against the bearing lug. By adjusting the sleeve 34 the tension of the spring 38 may be varied. The end 39 of the sliding rod 33 is adapted to engage the arm 8 of the movable electrode when the parts are in idle or released position as shown in Fig. 2. The end 39 of the sliding rod 33 is spaced from the adjacent face of the arm 8. This spacing is sufficient so that as the ignition points 6 and 7 wear the spring 9 can turn the movable electrode so as to maintain these ignition points in contact. This results in the ignition points always being in contact when the parts are in released or idle position. The trip lever is operated in the well known way in this type of devices.

As clearly shown in Fig. 2 of the drawings, the trip lever is operated by a push rod 40. This push rod is provided with a shoulder 41 which is adapted to engage a projecting lug 42 at the bottom of the trip lever. A projecting arm or cam 43 serves to force the

push rod 40 downwardly and release the shoulder 41 from the projecting lug 42. As the push rod moves to the left, as viewed in Fig. 2, the trip lever will be turned in a clockwise direction compressing the torsional spring 26, thus storing up power in said spring. The upper end of the trip lever at this time is moved away from the end 36 of the sliding rod 33. The rotor shaft is also 10 oscillated by this movement of the trip lever as the two are connected together and moving as one. When the shoulder 41 is tripped or disengaged from the trip lever, the torsional spring will rotate the trip lever and 15 the rotor shaft in a counter-clockwise direction, the upper end of the trip lever will strike the sliding rod 33 a blow which will force the rod to the left, as viewed in Fig. 2, compressing the spring 38 which serves in a 20 measure as a buffer spring, preventing wear on the parts. The other end 39 of this sliding rod 33 will be caused to make contact with the arm 38 so as to separate the points 6 and 7. The parts are so adjusted and timed 25 that the points will be separated just as the rotor reaches the point of maximum current generation. When the trip lever has reached the point indicated in Fig. 2, the torsional spring will substantially have spent 30 the power stored therein so that there is very little tension in the spring tending to turn the trip lever in a counter-clockwise direction at this time. The tension of the spring 38 is greater than the tension of the spring 26 35 when the parts are in the idle or released position, so that this spring 38 returns the push rod 33 until the stop collar limits this movement. This retracting or returning movement of the rod 33 moves the end 39 out 40 of engagement with the arm 8 and permits the ignition points to make contact through the action of the spring 9. As clearly shown in the drawings, the torsional spring is mounted on a sleeve projecting from the trip 45 lever and this prevents any jam or wear on the torsional spring through the movements of the trip lever. Furthermore, the torsional spring bears on the trip lever through an interposed roller which not only reduces the 50 friction due to the movement of the spring on the trip lever but also prevents the projecting end 28 of the spring from breaking.

In Fig. 5 of the drawings I have shown a slightly modified form of the invention in 55 that the rod for supporting the trip lever 19 is extended so as to engage the rotor shaft of the generator. The rod is indicated at 18^a. Said rod is rigidly carried by the bracket 1 but projects entirely through the 60 trip lever and the outer end of this rod extends into a recess or housing 18^b in the end of the rotor shaft 11. The rod 18^a insures the co-axial alinement of the rotor shaft and the trip lever and prevents any displacement 65 of the generator.

The generator is supported by the rod 10 and is keyed thereto, in the form of the invention shown in Fig. 1. With this rod 18^a, however, extending into the rotor shaft, the keyway connection between the perforated 70 lug 13 and the rod 10 may be done away with. In other words, the rod 18^a will prevent the generator from turning axially about the rod 10. From the above it will be apparent that in case of any break down 75 of the generator the same may quickly be removed as a unit by removing the single nut 16 and thus slipping the generator off from the rod 10, the coupling between the rotor shaft and the trip lever being readily disconnected. On the other hand, when the parts are assembled, as clearly shown in the drawings, the generator will be rigidly supported by the bracket so that it is impossible 80 for the rotor shaft to get out of timing with 85 the electrodes due to any false or improper movements of the generator on the bracket.

It will be further noted that my improved ignition system which includes the ignition devices and the generator and the actuating 90 mechanism therefor, are all mounted on a single bracket which may be readily removed and replaced. The parts may be all assembled at the factory and placed on an engine and without requiring adjustment 95 thereof.

It will also be noted that I have reduced the number of parts over that contained in the structures heretofore used and have greatly simplified the structure, as well as 100 rendering the same more durable and lasting.

It is obvious that minor changes in the details of construction and arrangement of parts may be made without departing from the spirit of the invention as set forth in the 105 appended claims.

Having thus described my invention, what I claim as new and desire to secure by Letters Patent, is: —

1. The combination of an ignition generator having a rotor shaft, a trip lever connected to and movable with said rotor shaft, a torsional spring for actuating the trip lever and rotor shaft and an ignition device including a movable electrode, said trip lever operating to actuate the movable electrode. 110

2. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes and means operated by the trip lever for separating the ignition 115 points. 120

3. The combination of an ignition generator having a rotor shaft, a trip lever connected to and movable with said rotor shaft, a torsional spring for actuating the 125 points. 130

trip lever and rotor shaft, ignition electrodes, one of which is movable, ignition points carried by the electrodes, a member disposed between the movable electrode and the trip lever and adapted to be moved by a blow from the trip lever for separating the ignition points.

4. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes, a member disposed between the movable electrode and the trip lever and adapted to be moved by a blow from the trip lever for separating the ignition points, a separate spring for retracting the said member so as to permit the ignition points to close.

5. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes, a member disposed between the movable electrode and the trip lever and adapted to be moved by a blow from the trip lever for separating the ignition points, a separate spring for retracting the said member so as to permit the ignition points to close, a stop for limiting the movement of said member through the action of its spring.

6. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes, a member disposed between the movable electrode and the trip lever and adapted to be moved by a blow from the trip lever for separating the ignition points, a separate spring for retracting the said member so as to permit the ignition points to close, a stop for limiting the movement of said member through the action of its spring and means for increasing the tension of the spring for operating the said member.

7. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes, a member disposed between the movable electrode and the trip lever and adapted to be moved by a blow from the trip lever for separating the ignition points, a separate spring for retracting the said member so as to permit the ignition points to close, a stop for limit-

ing the movement of said member through the action of its spring, said member when in retracted position being out of contact with the movable electrode so as to permit the ignition points as they wear to still be 70 brought into contact.

8. The combination of an ignition generator having a rotor shaft, a trip lever connected to and movable with said rotor shaft, a torsional spring for actuating the trip lever and rotor shaft, ignition electrodes, one of which is movable, ignition points carried by the electrodes, a member disposed between the movable electrode and the trip lever and adapted to be moved by a blow from the trip lever for separating the ignition points, a separate spring for retracting the said member so as to permit the ignition points to close, a stop for limiting the movement of said member through 80 the action of its spring and means for increasing the tension of the spring for operating the said member, the tension of the spring operating said member being less than the tension of the torsional spring 85 when released so that said member may be moved to the limit of its stop.

9. The combination of an ignition generator having a rotor shaft, a trip lever connected to and movable with said rotor shaft, a torsional spring for actuating the trip lever and rotor shaft, a rod disposed between the trip lever and the movable electrode, said rod being adapted to be moved endwise by a blow from the trip lever for actuating the movable electrode to separate the ignition points, a spring for moving said rod toward the trip lever to permit the ignition points to be brought into contact, said rod being normally out of contact with the movable electrode so that the ignition points as they wear will still be in contact.

10. The combination of an ignition generator having a rotor shaft, a trip lever connected to and movable with said rotor shaft, a torsional spring for actuating the trip lever and rotor shaft, a rod disposed between the trip lever and the movable electrode, said rod being adapted to be moved endwise by a blow from the trip lever for actuating the movable electrode to separate the ignition points, a spring for moving said rod toward the trip lever to permit the ignition points to be brought into contact, said rod being normally out of contact with the movable electrode so that the ignition points as they wear will still be in contact, a stop for limiting the movement of the rod and means for varying the tension of the spring moving said rod.

11. The combination of an ignition generator having a rotor shaft, a trip lever connected to and movable with said rotor shaft, a torsional spring for actuating the trip lever and rotor shaft, a rod disposed be- 125 130

between the trip lever and the movable electrode, said rod being adapted to be moved endwise by a blow from the trip lever for actuating the movable electrode to separate 5 the ignition points, a spring for moving said rod toward the trip lever to permit the ignition points to be brought into contact, said rod being normally out of contact with the movable electrode so that the ignition 10 points as they wear will still be in contact, a stop for limiting the movement of the rod and means for varying the tension of the spring moving said rod, the tension of said spring for moving the rod being greater 15 than the tension of the torsional spring when released whereby said rod may be moved to the limit of the stop to permit the ignition points to move into contact.

12. The combination of an ignition generator having a rotor shaft, a trip lever connected to and movable with said rotor shaft, a torsional spring for actuating the trip lever and rotor shaft, an arm carried by the movable electrode outside of the engine 25 cylinder, a rod disposed between the end of the arm and the end of the trip lever, spaced bearings in which said rod reciprocates, a collar secured to the rod and adapted to engage one of said bearings to limit the movement of the rod, a spring encircling the rod and adapted to move the rod so as to cause the stop to engage the bearing, said rod being out of contact with the arm on the movable electrode when limited by said 30 stop, the tension of the spring on said rod being greater than the tension of the torsional spring when in released position whereby said trip lever may be in contact with the end of said rod when in idle or released position.

13. The combination of an ignition generator having a rotor shaft, a trip lever arranged in co-axial alinement with the rotor, means for connecting the trip lever 45 to the rotor shaft, a torsional spring disposed co-axially with the trip lever and adapted to actuate said trip lever and rotor shaft, ignition electrodes, one of which is movable and ignition points carried by said 50 electrodes, said trip lever operating to separate the ignition points.

14. The combination of an ignition generator having a rotor shaft, a trip lever co-axial with said rotor shaft, a projecting 55 sleeve carried by the trip lever, a torsional spring encircling said projecting sleeve and connected with the trip lever for actuating the same and means for connecting the trip lever to the rotor shaft.

15. The combination of an ignition generator having a rotor shaft, a trip lever co-axial with said rotor shaft, a projecting 60 sleeve carried by the trip lever, a torsional spring encircling said projecting sleeve and connected with the trip lever for actuating

the same and means for connecting the trip lever to the rotor shaft, ignition electrodes, ignition points carried thereby, one of said electrodes being movable and operated by the trip lever.

16. The combination of an ignition generator having a rotor shaft, said rotor shaft having a coupling member carried thereby, a trip lever co-axial with said rotor shaft, a coupling member integral with said trip 75 lever, one of said coupling members having concentrically arranged projecting lugs and the other of said members having recesses adapted to fit and receive said lugs whereby the movements of the trip lever are 80 imparted to the rotor shaft and spring means for actuating the trip lever and rotor shaft.

17. The combination of an ignition generator having a rotor shaft, said rotor shaft 85 having a coupling member carried thereby, a trip lever co-axial with said rotor shaft, a coupling member integral with said trip lever, one of said coupling members having concentrically arranged projecting lugs 90 and the other of said members having recesses adapted to fit and receive said lugs whereby the movements of the trip lever are imparted to the rotor shaft, and a torsional spring co-axially arranged with the trip 95 lever and rotor shaft for actuating said trip lever and rotor shaft.

18. The combination of an ignition generator having a rotor shaft, said rotor shaft having a coupling member carried thereby, 100 a trip lever co-axial with said rotor shaft, a coupling member integral with said trip lever, one of said coupling members having concentrically arranged projecting lugs and the other of said members having recesses adapted to fit and receive said lugs whereby the movements of the trip lever are 105 imparted to the rotor shaft, said trip lever having a sleeve formed integral therewith and projecting from the side thereof opposite the coupling member, a torsional spring surrounding said sleeve, said torsional spring being connected to the trip 110 lever for actuating the same.

19. The combination of an ignition generator having a rotor shaft, a trip lever for operating said rotor shaft, a torsional spring for actuating the trip lever, one end of said torsional spring being fixed and a roller carried by the other end of said torsional 120 spring and adapted to bear against the face of the trip lever.

20. The combination of an ignition generator having a rotor shaft, a trip lever for operating said rotor shaft, a torsional spring 125 for actuating the trip lever, one end of said torsional spring being fixed and a roller carried by the other end of said torsional spring and adapted to bear against the face of the trip lever, said roller having a pro- 130

jecting flange extending alongside of the trip lever.

21. The combination of an ignition generator having a rotor shaft, a supporting bracket, ignition electrodes mounted in said bracket, one of which is movable, a rod carried by said bracket and projecting outwardly therefrom, a perforated lug attached to said generator and adapted to receive said rod whereby said generator is supported and means for actuating the rotor shaft and the movable electrode.

22. The combination of an ignition generator having a rotor shaft, a supporting bracket, ignition electrodes mounted in said bracket one of which is movable, a rod carried by said bracket and projecting outwardly therefrom, a perforated lug cast integral with the rotor housing and adapted to receive said rod for supporting said generator, means for actuating said rotor shaft and said movable electrode.

23. The combination of an ignition generator having a rotor shaft, a supporting bracket, ignition electrodes mounted in said bracket one of which is movable, a rod carried by said bracket and projecting outwardly therefrom, a supporting means adapted to engage said rod, said supporting means being attached to the rotor housing and located within the magnets of the generator and means for actuating said rotor shaft and said movable electrode.

24. The combination of an ignition generator having a rotor shaft, a supporting bracket, ignition electrodes mounted in said bracket, one of which is movable, a rod carried by said bracket and projecting outwardly therefrom, a perforated lug cast integral with the housing of the rotor, means for keying said lug to said rod, a clamping nut for holding said perforated lug on said rod and means for actuating the rotor and the movable electrode.

25. The combination of an ignition generator having a rotor shaft, a supporting bracket adapted to be attached to the engine cylinder, ignition electrodes mounted in said bracket, one of which is movable, a projecting rod carried by said bracket and extending outwardly therefrom, a perforated lug attached to the generator and adapted to engage said rod for supporting the generator, a projecting member extending from said bracket in axial alignment with the rotor shaft, a trip lever mounted on said projecting member and turning freely thereon, said trip lever being connected to said rotor shaft, a torsional spring surrounding said projecting member, one end of said spring being connected to the bracket and

the other end thereof to said trip lever and means whereby said trip lever may actuate the movable electrode.

26. The combination of an ignition generator having a rotor shaft, a bracket adapted to be attached to the engine cylinder, ignition electrodes mounted in said bracket, one of which is movable, a projecting member carried by the bracket, means for attaching the generator to said member, a projecting rod extending from the bracket, said rotor shaft having a recess formed in its outer end adapted to receive said projecting rod, a trip lever mounted to turn freely on said rod and connected to said rotor shaft and spring means for actuating said trip lever and movable electrode.

27. The combination of an ignition generator having a rotor shaft, a bracket adapted to be attached to the engine cylinder, ignition electrodes mounted in said bracket, one of which is movable, a projecting member carried by the bracket, means for attaching the generator to said member, a projecting rod extending from the bracket, said rotor shaft having a recess formed in its outer end adapted to receive said projecting rod, a trip lever mounted to turn freely on said rod, a torsional spring surrounding the rod, one end of said spring being connected to the bracket and the other end of said spring bearing against the trip lever, said trip lever being connected to the rotor shaft and adapted to actuate said rotor shaft and said movable electrode.

28. The combination of an ignition generator having a rotor shaft, a bracket adapted to be attached to the engine cylinder, ignition electrodes mounted in said bracket, one of which is movable, a projecting member carried by the bracket, means for attaching the generator to said member, a projecting rod extending from the bracket, said rotor shaft having a recess formed in its outer end adapted to receive said projecting rod, a trip lever mounted to turn freely on said rod, a torsional spring surrounding the rod, one end of said spring being connected to the bracket and the other end of said spring bearing against the trip lever, said trip lever being connected to the rotor shaft and adapted to actuate said rotor shaft and said movable electrode, a roller carried by the end of the spring and bearing against the face of the trip lever.

In testimony whereof I hereunto affix my signature in the presence of two witnesses.

ALBERT ERICKSON.
